DISK TOOL

Frans O. Albertson, Sioux City, Iowa, assignor to
 Albertson & Company, Inc., Sioux City, Iowa,
 a corporation of Iowa

Application January 18, 1935, Serial No. 2,339

3 Claims. (Cl. 164—82)

The present invention relates to abrasive disk tools, and is particularly concerned with devices for enabling the users of abrasive disks or the like to fully utilize the abrasive area of the material of which the disk is made.

The abrasive disks to which reference has been made are used upon flexible supporting pads of the type covered by my prior Patent No. 1,882,693, October 18, 1932, Abrasive device, and it is frequently found that the outer edge of the disk is subjected to the greatest amount of use and wear. The central portion of the disk may then still be in good condition and capable of further use.

One of the objects of the invention is the provision of an improved tool by means of which the used portion of the disk may be cut off.

Another object of the invention is the provision of an improved cutting tool by means of which the used parts of an abrasive disk may be trimmed off and the abrasive put in proper condition for use on a smaller supporting pad.

Another object of the invention is the provision of an improved tool of the class described, which is adapted to be used for trimming abrasive disks of various sizes to successively smaller sizes suitable for various smaller supporting pads.

Another object of the invention is the provision of an improved disk cutting tool of the class described, which is simple, sturdy, economical and peculiarly adapted to the quick and clean cutting or trimming of abrasive disks with a minimum amount of effort, in order to utilize fully all of the area of the abrasive material.

Other objects, features and advantages of the invention will be apparent from the following description and the accompanying drawing, in which similar characters of reference indicate similar parts throughout the several views.

Referring to the single sheet of drawings, Fig. 1 is a top plan view of the present tool;

Fig. 2 is an elevational view in partial section taken on the plane of the line 3—3 of Fig. 1, the cutting board and abrasive being shown in section;

Fig. 3 is a sectional view, with most of the parts of the tool in section, taken on the plane of the line 3—3 of Fig. 1, looking in the direction of the arrows;

Fig. 4 is a fragmentary detail sectional view, taken on the plane of the line 4—4 of Fig. 3, with the cutter in elevation;

Fig. 5 is a fragmentary detailed sectional view, taken on the plane of the line 5—5 of Fig. 3, showing the structure of the securing means for the cutter support.

The complete tool equipment preferably includes a relatively hard flat cutting board such as a piece of oak or other suitable material, against which the abrasive sheet may be placed for the cutting operation.

The board 10 is preferably provided with a centrally located aperture 11, which is of materially larger size than the downwardly projecting trunnion 12 which passes through the aperture in the disk 13. The aperture 11 is larger than the trunnion 12 so that the grooving which results from a cutting operation comprising a circle on the board will not always strike the same part of the board. However, the trunnion 12 and aperture 11 serve to substantially center the cutting tool with respect to the board 10.

The abrasive disks 13 are usually made of relatively stiff material covered with abrasive such as emery or carborundum upon the one side, and they are formed with a centrally located aperture 14 for passing a drive shaft or securing screw bolt and a preformed depression 15 in the face of the disk for receiving the flat head of the securing member which passes through the aperture 14. The abrasive should be placed face downward upon the board 10, and the trunnion 12 of the tool should be inserted in the aperture 14 for the cutting operation.

The cutting tool preferably comprises a substantially cylindrical stud 16 provided with a reduced cylindrical portion comprising trunnion 12, and with the intermediate annular shoulder 17. The cylindrical stud 16 is provided with an axially threaded bore 18 for receiving the threaded end of the screw bolt 19, the head 20 of which retains 35 the knob 21 which is rotatably supported on the screw bolt 19.

The stud 16 is also provided with a transverse cylindrical bore 22, within which is fixed the cylindrical end 23 of a radial arm 24 by means of 40 a transverse pin 25. The arm 24 is preferably rectangular in cross section except for the cylindrical end 23, and is preferably provided with a plurality of stop members 25, 26, 27. These stop members may comprise screw bolts which are 45 threaded home in the complementary threaded bores provided in the radial arm 24 and located at suitable radii from the center of the stud 16.

The standard size of abrasive disk is always one eighth of an inch over size so as to overlap the holder, and on some jobs even greater overlaps are desired so that for such purposes the holder may have its cutter set at any desired radius. However, the usual sizes of abrasive disks are nine inches, seven inches, five inches, 55

and three inches, and the stops 25, 26, 27 are so located that when the side of the holder 28 engages the head of any stop or bolt 25-27, the cutter 29 is located at a suitable radius to cut the standard size of disk. The largest size of disk may be cut by placing the holder 28 outside of the stop 25 on the arm 24.

The holder 28 comprises a block of steel, all of the parts of the tool being made of steel or other suitable material, and the block or holder 28 is provided with a transverse aperture 30 of rectangular shape and complementary to the shape of the arm 24 so that the block or holder 28 is slidably mounted on the arm 24.

15 Transverse rotation is, of course, prevented by the non-circular shape of the arm 24 and aperture 30, and therefore the holder is always held with its axis in alignment with the axis of a stud 16, which is the center of rotation.

20 The holder 28 is also provided with a threaded bore for receiving a clamping screw by means of which it may be secured at any desired position on the arm 24.

Upon its upper end the holder 28 is provided 25 with a threaded bore 31 for receiving the threaded end of the screw bolt 34 which rotatably supports the knob 35. In its lower end the holder is provided with a longitudinally extending slot 36 of sufficient width to rotatably receive the 30 circular cutter 29. The block 28 is also provided with the bore 37 communicating with counter-bore 38 for receiving the cylindrical head 39 and the cylindrical body 40 of a screw bolt which serves as a journal for the cutter 29. The screw 35 bolt 39, 40 may also be provided with an annular shoulder 41 so that the bolt may be secured tightly in place by a nut 42, the cutter 29 being mounted for rotation on the cylindrical portion 39.

Cutter 29 comprises a circular disk of best 40 hardened tool steel provided with a bevel 43 forming a cutting edge at the periphery of the disk. The cutter is preferably arranged with its bevel outward with respect to the center of the tool.

45 In order to hold the abrasive disk in place the trunnion 12 also rotatably supports or is rotatably supported upon a cup-shaped member 44 which may be formed of a sheet metal stamping having a circular body and a downwardly extending cylindrical flange 45. An upwardly extending cylindrical flange 46 forms a bearing for the trunnion 12 by engaging the annular shoulder 17.

The member 44 is preferably provided with a 50 washer plate 47 which may be spot welded to the body of the member 44 at a plurality of points, and which provides the body with a relatively sharp retaining shoulder at the point 48 for engaging the split wire ring 49. The split wire ring 55 is sprung into a groove 50 suitably located in the trunnion 12 so as to retain the member 44 on the trunnion 12. Member 44 is, therefore, adapted to rotate with respect to trunnion 12 and may be utilized by means of the knob 21 for pressing 60 down on the disk 13 at the end 51 of the flange 45, the disk being clamped between the flange 45 and the board 10.

The method of use of the tool is as follows: 65 The abrasive is placed face down on the board 10 and the cutter 29 located at the proper radius so as to trim off the used portion of the disk. The knob 21 may be pressed down to hold the disk 13 in fixed position on the board and the cutter may be worked back and forth by pressing 70 down on the knob 35 and moving it back and

forth in a circle determined by the arm 24. As the cutter 29 cuts through the abrasive disk, the operator may relieve the pressure on the knob 21 and taking hold of the edge of the disk rotate the disk around to such a point that it is again in convenient position to cut a short arc of a disk by means of the cutter 29, and thus by successive cuts the used part of the disk is cut from the periphery of the disk and the disk is reduced in size to the next standard abrasive disk 10 for a smaller supporting pad. When the edge of the disk has again been used, assuming that the center portion is still in good condition, a further cut may be made off the edge of the disk, and thus the disk may be used a plurality of times 15 until its use on the smallest type of supporting pad leaves hardly any exposed portion of the disk for use.

It will thus be observed that I have invented 20 an improved tool by means of which abrasive disks of the type described may be trimmed down and the abrasive area thereof fully utilized, although the greatest amount of wear or use comes at the edge of the abrasive disk.

The present tool is simple, sturdy, compact 25 and will save its cost in a very short time in the saving effected by more economical use of abrasive disks. The purchaser or user may then buy the larger sizes of disks and use the central portions of the larger disks for smaller abrasive 30 disks by trimming off the consumed or used portion of the abrasive disk.

While I have illustrated a preferred embodiment of my invention, many modifications may be made without departing from the spirit of the 35 invention, and I do not wish to be limited to the precise details of construction set forth, but desire to avail myself of all changes within the scope of the appended claims.

Having thus described my invention, what I 40 claim as new and desire to secure by Letters Patent of the United States, is:

1. In a disk cutting tool, the combination of a supporting shaft with a radially extending arm, a holder adjustably mounted on said arm, a disk 45 cutter carried by said holder, a clamping member carried by said shaft comprising a cup shaped member having a depending flange for engaging and holding a sheet, said shaft projecting into said cup to engage in an aperture in the sheet 50 to hold said sheet in predetermined position, said shaft having a groove located therein, and a resilient metal member engageable in said groove and projecting therefrom sufficiently to engage and retain said cup shaped member on said shaft.

2. In an abrasive disk tool, the combination of 55 a suitable support with a tool having a vertically extending trunnion, a member having a depending flange carried by said trunnion for engaging and securing an abrasive sheet when pressure is applied to said handle, a radially extending arm carrying a cutter for making a circular cut on a sheet of abrasive material, said cutter being slidably mounted on said arm, a plurality of stops located on said arm for securing said cutter in 60 any of a plurality of predetermined positions, said cutter being carried by a metal member slidably mounted on said arm, and a handle rotatably mounted on said member for the application of pressure to said cutter.

3. In an abrasive disk tool, the combination of 65 a suitable support with a tool having a vertically extending trunnion, a relatively hard flat cutting board having a centrally located aperture of materially larger size than the trunnion, a handle 70

carried on said trunnion, a member having a depending flange carried by said trunnion for engaging and securing an abrasive sheet on said cutting board when pressure is applied to said handle, a radially extending arm carrying a cutter for making a circular cut on a sheet of abrasive material, said cutter being slidably mounted

on said arm, and means for securing said cutter in any of a plurality of predetermined positions, said cutter being carried by a metal member slidably mounted on said arm, and a handle rotatably mounted on said member for the application of pressure to said cutter.

FRANS O. ALBERTSON.
